TRAFFIC SIGNAL LENS

John R. Miles, Glenview, Ill., assignor to Gulf +
Western Industries, Inc., New York, N.Y.

Filed Feb. 8, 1971, Ser. No. 113,517

Term of patent 14 years

Int. Cl. D26—06, 05

U.S. Cl. D48—32

FIG. - 1

FIG. - 2

FIG.-4

FIG.-5

FIG. 1 is a top plan view of a traffic signal lens showing my design;

FIG. 2 is a side elevational view thereof;

FIG. 3 is a bottom plan view thereof;

FIG. 4 is a cross-sectional view taken on line 4—4 of FIG. 3;

FIG. 5 is a cross-sectional view taken on line 5—5 of FIG. 3.

The shading in FIGS. 3, 4 and 5 indicates planar surface portions on the inner surface of the lens.

I claim:

The ornamental design for a traffic signal lens, as shown and described.
